NOZZLE CHEST ATTACHMENT

Hans P. Dahlstrand, Wauwatosa, Wis., assignor
to Allis-Chalmers Manufacturing Company,
Milwaukee, Wis., a corporation of Delaware

Application November 26, 1937, Serial No. 176,411

6 Claims. (Cl. 253—78)

This invention relates to high temperature turbine construction and particularly to a means for introducing steam to a turbine in such manner as to minimize the effect of high temperature on the casing thereof.

It is an object of this invention to provide a means for attaching a nozzle chest to a turbine casing whereby transfer of heat from the nozzle chest to the casing is reduced.

Further objects of this invention are: the provision of an improved means for introducing high temperature steam into a turbine casing; the provision of a welded connection between the turbine casing and nozzle chests located therein; the provision of a neck portion extending outwardly from the turbine cylinder, the nozzle chest being attached to the outer end of said neck portion; and a unitary connection between a steam inlet pipe, the turbine casing and the nozzle chest, or between a steam valve body, the turbine casing and the nozzle chest.

It has heretofore been common practice to provide a flanged connection between the steam inlet pipe or valve body and turbine casing, and between the casing and nozzle chest of an impulse or an impulse reaction turbine. Because of the high temperature of the steam introduced into the turbine and the large area of contact between steam inlet pipe and turbine casing provided by such flanged connection, sufficient heat was transferred to the casing at the point of steam inlet to produce excessive local expansion which resulted in distortion of the turbine cylinder. Another prior practice is to make the nozzle chest integral with the turbine casing. This also results in undesirable local heating of the cylinder, causing distortion thereof, accompanied by blade interference and steam leakage.

In accordance with the present invention, the nozzle chests are welded to the turbine casing, the weld being preferably at a point spaced from the cylinder proper by a neck portion made integral with the cylinder. The weld may be utilized to connect a steam conduit, a nozzle chamber and the turbine casing at one welded joint; and the cross-sectional area of the weld is preferably no greater than the cross-sectional area of the parts to be connected. In this way the joint is heated uniformly, avoiding distortion thereof; and the heat transfer area between the nozzle chest and the casing is reduced.

In the drawing,

Fig. 1 illustrates a preferred construction in accordance with this invention, showing an elevation sectional view of an impulse or impulse

reaction turbine taken in a plane perpendicular to the axis of the turbine, the spindle of the turbine not being shown.

Fig. 2 is a fragmentary sectional elevation view of a modified construction. 5

Referring to Fig. 1, a generally cylindrical turbine casing 10 is provided with a plurality of individual nozzle chests 11, 12, 13, each of which carries a plurality of removable nozzles 15. Each nozzle has an integral steam inlet 20. 10 High temperature steam is admitted to the turbine by means of steam pipes 14. The admission of steam may be regulated by hand valves 16 having valve casings 17, or the steam may be admitted into the nozzle chest directly, as shown 15 with respect to central nozzle chest 12.

To remove the points of steam inlet from contact with the casing 10, nipples or neck portions 18 are provided on casing 10 at points of steam admission, and nozzle chests 11, 12 and 13 are 20 connected to inlet pipes 14 (or valve casings 17) at the outer end of neck portions 18. This connection of nozzle chambers and steam inlets (or valve casings) to the outer end of neck portions 18 is preferably effected by means of welds 19. 25 The welds not only avoid the weight and difficulty of flange connections, but provide a contact area of greatly reduced cross section between the highly heated valve body or steam pipe and nozzle chamber on the one hand and the 30 relatively cool casing 10 on the other, thereby reducing heat transfer to the casing. The cross-sectional area of the weld 19 is preferably not substantially larger than the cross-sectional area 35 of the parts being joined together, thereby reducing the heat transfer area between live steam and the turbine casing, and resulting in more uniform heating of the joint. Moreover, even if the outer end of neck portions 18 becomes hot, the expansion thereof does not result 40 in high stresses in the main turbine casing 10. Since the heat from valve casing 17 or pipe 14 must flow through the length of neck portion 18, only a relatively small proportion of the heat is 45 transferred to the casing itself with this construction. In this way distortion of the turbine casing, which is likely to be accompanied by interference with the blading and steam leakage at the joints is eliminated.

The construction shown in Fig. 2 is generally 50 similar to that of Fig. 1, except that the weld 19' in this case connects only the nozzle chest and neck portion 18. The steam inlet portion 20' of the nozzle chest extends beyond neck portion 18, and may be connected to the valve casing 17 (or 55

steam conduit 14) either by a weld 22, or by a flanged connection. This indicates that it is not necessary to connect all three members (neck 18, nozzle chest inlet 20 and valve casing 17) by a single weld in order to obtain some of the advantages of this invention.

While this construction has been described with reference to a steam turbine it is equally applicable to gas turbines, or any other case where it is desired to lead a high temperature fluid into a casing without causing undesirable distortion therein.

While the invention has been illustrated by a specific construction, it is not desired to limit the scope thereof except as defined by the claims appended hereto.

It is claimed and desired to secure by Letters Patent:

1. In a turbine, a casing, a nozzle chest provided with a steam inlet and means for supporting said nozzle chest in said casing consisting of a welded joint between said steam inlet and said casing, said welded joint being the only area of close contact between said nozzle chest and said casing, whereby a reduced heat transfer area is obtained between said nozzle chamber and said casing.
2. In a turbine, a casing, a nozzle chest provided with a steam inlet and means for supporting said nozzle chest in said casing comprising a neck integral with said casing and extending

therefrom and means consisting of a contact area not substantially greater than the cross-section area of said neck for supporting said nozzle chamber from the outer end of said neck, whereby the heat transfer connection between said nozzle chest and said casing is increased in length and limited in cross-sectional area.

3. In a turbine, a casing, a nozzle chest provided with a steam inlet and means for supporting said nozzle chest in said casing consisting of a neck 10 integral with said casing and extending therefrom and a single welded connection between said nozzle chest steam inlet and the outer end of said connection.

4. In a turbine, a casing, a nozzle chest mounted within said casing, a conduit for admitting steam to the turbine, and a single welded joint uniting said steam conduit, said nozzle chest and said casing.

5. A construction as claimed in claim 4, in which the cross-sectional area of the welded joint is not substantially greater than the normal cross-sectional area of said conduit.

6. In a turbine, a casing provided with a neck portion extending therefrom, a steam inlet valve body, a nozzle chest mounted in said casing, and a single welded connection joining the outer end of said neck portion with said valve body and said nozzle chest.
